UNITED STATES PATENT OFFICE

164,875

SHELF FOR HOLDING TOILET ARTICLES

Jose Brito Perez, Habana, Cuba

Application August 4, 1950, Serial No. 11,593
In Cuba June 19, 1950

Term of patent 14 years

(Cl. D33—3)

To all whom it may concern:

Be it known that I, Jose Brito Perez, a citizen of the Republic of Cuba, residing at Habana, Cuba, have invented a new, original, and ornamental Design for a Shelf for Holding Toilet Articles of which the following is a specification, reference being had to the accompanying drawing, forming a part hereof.

I claim:

The ornamental design for a shelf for holding toilet articles as shown.

JOSE BRITO PEREZ.
